CLAIM

The ornamental design for an audio visual appliance, as shown and described.

DESCRIPTION

FIG. 1 is a left-side perspective view of an audio visual appliance showing my design;
FIG. 2 is a right-side perspective view thereof;
FIG. 3 is a front perspective view thereof;
FIG. 4 is a rear view thereof;
FIG. 5 is a left-side perspective view thereof with a display panel in a fully open position;
FIG. 6 is a right-side perspective view thereof with the display panel in a closed position;
FIG. 7 is a left-side perspective view thereof with the display panel in the closed position;
FIG. 8 is a bottom view thereof with the display panel in the open position;
FIG. 9 is a top view thereof;
FIG. 10 is a right-side view thereof;
FIG. 11 is a left-side view thereof; and,
FIG. 12 is a bottom and rear perspective view thereof. The broken lines shown in the drawings depict portions of the audio visual appliance that form no part of the claimed design.

1 Claim, 9 Drawing Sheets
